UNITED STATES PATENT OFFICE

CYRUS A. LELAND, JR., OF DES MOINES, IOWA

WATER HEATER

Application filed November 24, 1930. Serial No. 497,826.

My invention relates particularly to water heaters of the type used for furnishing hot water for domestic purposes, but is not confined to such use.

5 This application is a continuation in part of my previous application, Serial No. 422,051, filed January 20, 1930.

One of the objects of my invention is to provide a water heater of simple construction, which can be manufactured and installed at minimum first cost.

10 A further object of my invention is to provide such a water heater of such construction and arrangement of parts as to afford high efficiency for heating a maximum volume of water with a minimum use of gas or other heating means.

Another purpose is to provide such a structure with a "low standby", to-wit, low cost of 15 operation when water is not being used.

Still a further object is to provide a heater having "quick recovery", to-wit, which will quickly provide an additional supply of hot water after water previously heated has been 20 used.

These desirable results of low first cost, manufacture and installation, low operating cost and "quick recovery" I have attained by combining in my heater a number of 25 features including the surrounding of the combustion chamber and flue with water, the use of the principle of counter-flow of combustion gases and water, the employment of a down-draft arrangement which is balanced, the use of a relatively long horizontal tank with the combustion chamber at one end and extending quite close to the top and near the hot water outlet, which with other features makes it possible to heat a small 30 amount of water very quickly, and finally the arrangement of the cold water inlet and hot water outlet at such points as to make the best use of the other features of construction just mentioned.

45 With these and other objects in view, my invention consists in the construction, arrangement and combination of the various parts of my water heater, whereby the objects contemplated are attained, as hereinabove more fully set forth, pointed out in my

claims, and illustrated in the accompanying drawings, in which:

Figure 1 is a perspective view of a water heater embodying my invention.

55 Figure 2 is a central, section, vertical, detail view of the same.

Figure 3 is a transverse, vertical, sectional view taken on the line 3—3 of Figure 1; and

60 Figure 4 is a sectional view on the line 4—4 of Figure 1, showing a water inlet.

My heater is of the automatic type in which means is provided for automatically maintaining the temperature of the water.

65 There are certain requisites for a satisfactory commercial hot water gas heater for residences and domestic use. They have been indirectly referred to before and may again be summarized as follows:

70 1st. The first cost of the heater must be low. This means that the structure must be simple so that the manufacturing cost may be kept down, and it also means that the heater must be such that the cost of installation will be reasonable.

75 2nd. The operating cost must be kept down. To accomplish this, the cost while the burner is on full must be reasonable and the standby cost must be low. One of the great objections to many heaters is their high standby cost,—(their cost when no water is being drawn).

80 3d. A good heater must have a "quick recovery". This means that after water has been drawn from the tank, the heater must be such as to heat water quickly enough, so that a supply of hot water is always maintained.

85 In the gas industry, it has been very difficult to attain all of these objects, and so far as I know, they have not been satisfactorily attained in any commercial product. In some heaters, the operating cost is high and the "recovery" is quick, and in others the operating cost is low but the "recovery" is very slow.

90 I have produced a heater in which all of these objects are attained by a proper combination and arrangement of parts, using the five features mentioned above.

In my improved heater, I employ a tank indicated by the reference numeral 10 of the horizontally arranged type. I preferably, of course, coat the tank proper with suitable insulation 12.

I find that generally speaking the best results have been attained by using a tank approximately three times as long as it is high.

As shown in the drawings, the tank is illustrated as resting upon semi-circular hang-
ers 14, supported on suitable posts 16.

At one end of the tank, I provide one or more combustion chambers 18. The chamber 18 preferably has about the proportions relative to the tank as shown in Figures 2 and 3.

I preferably make the combustion chamber in the form of an upright cylinder reaching quite close to the top of the tank as shown.

The hot water outlet 20 is arranged at the top of the tank at one end above the combustion chamber 18, so that the hottest water will be drawn from the tank.

In the lower part of the combustion chamber is arranged a burner 24 to which fuel is supplied through a pipe 26. A control valve 28 may be provided close to the burner.

From the upper part of the combustion chamber, a down-draft flue 30 extends lengthwise of the tank 10 and downwardly to the opposite end thereof, through which this flue passes, as shown. The size of the flue and the length thereof as well as the size of the combustion chamber and the relative length and height of the tank have been determined upon by many experiments.

The arrangement of the combustion chamber and flue are such with relation to each other and the other parts that during stand-by periods, there is practically no draft through the flue. This is what I have called a "balanced draft arrangement".

The water inlet pipe 32 enters the end of the tank near the point where the flue emerges and is connected outside the tank with a supply pipe 34. The pipe 32 ends just inside the tank as shown in Figures 2 and 4.

For convenience in assembling the parts, the fuel supply pipe 26 is extended upwardly adjacent to the water supply pipe 34, alongside the inlet end of the tank.

A thermostatic unit 36 of known construction controls the valve 38 in the fuel line, according to the temperature of the water in the water inlet 32.

I will now describe the operation of my improved heater with reference to some of the features of its construction and the advantages resulting therefrom.

The burner may be ignited in the ordinary way. The heat in the combustion chamber is transferred to the water. The products of combustion flow downwardly through the flue 30 and are discharged at the intake end of the tank. Because the combustion chamber and flue are wholly surrounded by

water, I secure the maximum benefit of the heat.

On account of these facts and because the hot water outlet is close above the combustion chamber and because I use a horizontally arranged boiler, I can heat a very small amount of water without creating much circulation through the tank, and thus can maintain the hot water close to the outlet. This makes possible the heating of the water very quickly and makes possible a very rapid "recovery" after hot water has been used.

Because of the balanced arrangement of the down-draft, there is little waste of heat during standby periods.

It will be obvious that if the flue went up through the top of the tank, there would be a draft during stand-by periods and the air passing through the flue would take heat from the water. On the upturned outer end of the flue is the ordinary draft diverter hood 30°, located, as shown in the drawings, above the lower part and below the upper part of the flue 30, and serving in cooperation with the described arrangement of parts to provide for substantially balanced draft during standby periods. With the balanced draft arrangement, there is no such draft and no such loss of heat.

The arrangement of the inlet and outlet, of course, are such as to supply the water where the combustion gases are coolest and to permit drawing off the water just above the combustion chamber where the water in the tank is hottest.

The whole structure is very simple so that the cost of manufacture and installation is reduced to a minimum.

It is, of course, understood that a burner of the pilot type is used.

Thus a minimum amount of fuel is used during the stand-by.

There is a high efficiency during the heating of the water when it is being frequently drawn off. The maximum heat is adjacent to the outlet point of the tank and because of the horizontal arrangement of the tank, the upper hotter layer of water will be drawn off first and will furnish a considerable supply of water before the colder lower body of water is drawn off.

Such a heater is obviously economical because for ordinary purposes a small tank with a small burner may be used. The application of the heat is such that the mixing of hot and cold water is secured in just the proper extent for heating the water at the top of the tank and gradually lowering the level of the hot water.

These advantages of low cost of manufacture and installation, economical operating expense during heating and standby periods, and quick "recovery", I have attained in my present heater by reason of the particular structure employed and particularly by

means of the features of the wholly surrounded combustion chamber and flue, the employment of the down-draft which is balanced, the arrangement of the combustion 5 chamber on end, extended quite close to the top and near the outlet with the flue extending to the other end of the tank near the inlet, whereby I utilize the counter-flow principle.

10 I sometimes use more than one combustion chamber but when a plurality of such chambers is employed, they are all arranged near the outlet end of the tank and extend nearly to the top of the tank.

15 It will thus be clear that changes may be made in the details of the construction and arrangement of the parts of my improved heater without departing from the real spirit and purpose of my invention, and it is my 20 intention to cover by my claims any modified forms of structure or use of mechanical equivalents, which may be reasonably included within their scope.

I claim as my invention:

25 1. In a water heater of the kind described, a horizontally elongated tank, a combustion chamber in one end of the tank wholly received therein except at its bottom, extending close to the top of the tank a flue extending from the upper part of the combustion 30 chamber downwardly through the opposite end of the tank, a means associated with the flue, outside the tank, for providing balanced draft, a burner in the combustion 35 chamber, a pilot burner in the combustion chamber, means for controlling flow of fuel to burner, according to temperature of water near where it enters the tank, the tank having an inlet near the flue exit, and having 40 an outlet, just above the combustion chamber, whereby water in the tank is heated from the top down and quick recovery is afforded.

2. In a storage water heater, a heat insulated horizontally elongated tank, said tank having a water inlet and a water outlet, a vertical combustion chamber received therein at one end, spaced from the walls of the tank except at its bottom, a burner 45 in the combustion chamber, a pilot in the combustion chamber, a means for regulating the supply of fuel to the burner, responsive to temperature of water in the tank, a flue inclined from the upper part of the 50 combustion chamber, downwardly and through the opposite end of the tank near the bottom thereof, a draft retarder hood on the flue outside the tank not higher than the upper end of the flue in the tank, the 55 arrangement of said flue and hood providing for substantially balanced draft during 60 standby periods.

3. A storage water heater comprising a horizontally disposed elongated insulated 65 heating and storage tank, a metal housing

projecting upwardly from the bottom of said container and positioned near one end thereof and wholly received therein for providing a combustion chamber, a conduit for combustion gases in communication with said housing forming a continuation of said combustion chamber, said conduit being positioned lengthwise of the container and arranged with one end extending through the container in a plane lower than the point of connection of the conduit with said housing, a draft balancing means positioned on said conduit outside of said container to retard and balance the combustion within said chamber and conduit, a heating element within said chamber, said container having a water inlet near the outer end of the conduit, and an outlet, means adjacent the water inlet for automatically controlling the operation of said heating element, said water outlet being positioned close to combustion chamber whereby as the hottest water is withdrawn the heating element responds as a result of inrush of cold water through said inlet.
